UNITED STATES PATENT OFFICE.

HENRY H. SESSIONS, OF CHICAGO, ILLINOIS, ASSIGNOR TO THE STANDARD COUPLER COMPANY, OF NEW YORK, N. Y.

DRAFT-RIGGING FOR RAILWAY-CARS.

SPECIFICATION forming part of Letters Patent No. 653,822, dated July 17, 1900.

Application filed April 19, 1900. Serial No. 13,521. (No model.)

To all whom it may concern:

Be it known that I, HENRY H. SESSIONS, a citizen of the United States, residing at Chicago, in the county of Cook and State of Illinois, 5 have invented certain new and useful Improvements in Draft-Rigging for Railway-Cars; and I do hereby declare the following to be a full, clear, and exact description of the same, reference being had to the accompanying drawings, forming a part of this specification, and to the letters of reference marked thereon.

This invention relates to improvements in draft-rigging for railway-cars, and more especially to that class of draft-rigging designed for withstanding the strains incident to the use of heavy rolling-stock or long trains and wherein the power and action of the draft and buffering springs are augmented or modified by 20 the employment of friction-surfaces.

One object of the invention is to provide a draft-rigging capable of being readily substituted for the draft-rigging on rolling-stock now in use, dispensing, when desired, with 25 the use of draft-timbers and presenting, when applied, the greatest possible facilities for repairing or renewing worn or broken parts. Ordinarily the renewal of a broken or collapsed spring is an undertaking of some moment, requiring the labor of several workmen and an expenditure of considerable time 30 for its accomplishment. These objections are overcome by my present invention.

Another object of the invention is to provide a relatively light and cheap structure in 35 which the resistance of the draft and buffering springs shall be so augmented and modified that springs of ordinary standard size and power may be utilized for the draft-rigging of 40 rolling-stock of practically-unlimited weight and without occasioning shock or oscillating movement of any of the cars in starting, stopping, or varying speed and regardless of the length of the train.

45 The invention consists in certain novel details of construction and combinations and arrangements of parts, all as will be now described, and pointed out particularly in the appended claims.

50 Referring to the accompanying drawings, Figure 1 is a vertical section taken longitudi-

nally through a draft-rigging and end framing of a car, showing the application of my present improvement. Fig. 2 is a vertical section at right angles to Fig. 1. Fig. 3 is a 55 horizontal section taken centrally of the draft-bar. Fig. 4 is a top plan view, on a reduced scale, of the casting or housing for the working parts of the draft-rigging. Figs. 5 and 6 are front and side elevations, respectively, 60 of said casting or housing, the latter figure being partially broken away or in section. Fig. 7 is an end elevation of one of the transversely-movable wedge-blocks. Figs. 8 and 9 are side and face elevations of one of the 65 longitudinally-movable wedge-blocks.

Like letters of reference in the several figures indicate the same parts.

In applying a draft-rigging embodying my present invention to a car-frame of ordinary 70 construction a filling-piece A is preferably introduced between the two central longitudinal sills A' of the car-body to afford a solid plane base, to which the draft-rigging may be attached, although it will be understood that 75 the use of this filling-piece is optional, and the draft-rigging may, where so desired, be attached directly to the ordinary sills without the use of either a filling-piece or the draft-timbers ordinarily connected with the sills 80 and between which the usual draft-rigging is supported. To the sills A' and filling-piece A, when employed, a casting or housing B is attached by vertical bolts passing through any one of a series of holes b, Fig. 4, additional means for preventing the movement of 85 said housing or casting longitudinally being provided in the shape of flanges, lugs, or projections b' b'', which are adapted to be let into the sills or filling-pieces, as will be readily 90 understood from an inspection of Figs. 1 and 2. The casting or housing B consists of two guides or supports B', arranged transversely and in alinement with each other on opposite sides of a central passage-way into which the 95 draw-bar projects, as will be presently explained.

The two supports B' B'' are connected together by the central portion of the casting (see Fig. 5) and serve primarily as the guides 100 and supports for transversely-moving wedge-blocks C, which latter are mounted in said

supports B' and are guided and held in place by substantially-plane friction-faces c, which coöperate with corresponding seats c' in the supports B', whereby the transversely-movable wedge-blocks are held in alinement and are capable of a movement toward and from each other, but are held against tilting or inclination such as would cause them to bind in their supports or guides while moving in one direction or the other, and should pressure be applied to said wedge-blocks, tending to force them transversely of their line of movement, the surfaces c c' constitute friction-surfaces for retarding such movement.

15 The inner ends of the wedge-blocks C are provided with projecting inclined faces C' toward the front and back of the draft-rigging, while the top and bottom faces C² of such projecting portions are preferably substantially horizontal and flat for supporting that portion of the draft-rigging intermediate the two transversely-movable wedge-blocks.

The draft-bar E is provided with a yoke F, attached thereto in the usual manner by means of pins or rivets f, and the rear end of the draft-bar, together with said yoke, extends back between the two supports B' of the housing B, with the opening in the yoke in alinement with the wedge-blocks. Coöperating with said transversely-movable wedge-blocks are two oppositely-arranged wedge or, more properly, seat blocks G, mounted in opposite sides of the yoke F, the portions of said seat-blocks G which project into the yoke being formed to fit substantially accurately in the opening of the yoke, so as to move in unison with said yoke and draft-bar. The outer faces of the blocks G are formed with seats having inclined faces g, corresponding to and adapted to coöperate with the inclined faces C' of the transversely-movable wedge-blocks. The construction of the wedge or seat blocks G is well illustrated in Figs. 8 and 9, wherein it will be seen that each of said blocks is provided with a top and bottom web g', bridging the space between the inclined faces g and adapted, when the parts are assembled, to rest upon the faces C² of the blocks C and so support the inner end of the draft-bar and yoke, although it will be obvious to those skilled in the art that other suitable means for supporting said parts may be employed without departing from my invention.

55 The longitudinal movement of the draft-bar is limited by stops H, formed on the casting or housing B at front and rear and with which the blocks G contact under excessive strain, and the said stops H are preferably portions of the casting or housing B through which the attaching-bolts for securing the structure to the sills of the car are passed. The seat or wedge blocks G are provided with a central slot or elongated opening G', and the transversely-movable wedge-blocks C are provided with longitudinal openings C³, Fig. 7, said openings being adapted for the passage of a transverse bolt K, which extends

way through the draft-rigging from side to side and is adapted to retain cap pieces or plates L in position over the ends of the supports or guides B' of the housing B. Between these plates or caps L and the transversely-movable wedge-blocks suitable draft and buffer springs are arranged. As shown, the springs lettered M are coil-springs nested in the pocket formed by the outwardly-extending portions of the wedge-blocks C and adapted to force said wedge-blocks inwardly. The caps or plates L are provided with flanges l, adapted to fit in suitable seats l' in the outer ends of the guides or supports B', and a sufficient play is allowed between the outer ends of the wedge-blocks C and said plates or caps for permitting said blocks to move outwardly and the draft-bar to advance or recede to the full extent of its movement, and in order to provide for the utilization of springs of different standard lengths—such, for instance, as seven or eight inch springs—the said cap pieces or plates L are provided on one face 90 with projections L', which when turned inwardly to the position indicated in dotted lines in Fig. 3 will partially fill the spring-boxes and permit the use of shorter springs than would be practicable with the said caps 95 or plates turned as illustrated in full lines in said figure.

The through-bolt K may be provided with a nut or any other approved means for locking the caps or plates in position on each end 100 and notwithstanding the spring-pressure, and inasmuch as said bolt constitutes the means whereby the parts are held in their working positions, in so far, at least, as the yielding pressure is concerned, it is obvious that by 105 loosening the fastening means and removing one or the other, or both, of said caps or plates the springs may be withdrawn or the transversely-movable wedge-blocks may be withdrawn for renewal or repairs. Thus, it may 110 be said, it is only necessary to remove a single nut or fastening device for reaching and renewing any of the working parts, and the parts are of such shape and size that it is practicable for a single workman to make a complete 115 repair in a short space of time.

In order to insure a full contact of the inclined faces of the wedge-blocks under all conditions, a slight looseness or tilting movement is permitted the blocks G in the yoke 120 F, and to secure this without weakening the parts the said blocks G are each provided with a flange N, adapted to rest against the outer edge of the yoke F, and such flange has its inner face on opposite sides of the center 125 slightly inclined, forming a central bearing-point at N', Fig. 8, which normally rests against the edge of the yoke and permits the said block to rock slightly in one direction or the other, according to the direction of strain, or 130 to permit the working faces of the inclines of the two blocks to contact squarely when the draw-bar is moved in either direction. It is preferred also that the two blocks G

shall have their adjacent faces similarly formed to form central bearing-points at N', thus relieving the yoke and flanges N of strain, as the two blocks will form mutual supports under the action of the transversely-movable blocks and springs, relieving the yoke of all strain save the longitudinal strain incident to the draft or buffing movements.

- It is obvious that with a draft-rigging such 10 as described strains tending to move the draft-bar longitudinally will operate first against the friction-surfaces formed by the inclined faces g C', and this being converted into transverse movement of the blocks C will cause the 15 compression of the springs M, the movement of the blocks C, however, being retarded by the friction surfaces or faces c c', which latter faces, it will be noted, extend at right angles to the line of draft and are caused to 20 act by reason of the fact that the longitudinal movement of the draft-bar tends to crowd the transversely-movable wedge-blocks toward one side or the other of their guides, and thus we have double friction-surfaces for retarding or modifying the action of the springs. 25

It will be appreciated at once that the resistance of the springs is amplified greatly by the use of the wedge-blocks and that by substituting wedge-blocks having working 30 faces set at a greater or less inclination a variation in the resistance may be secured, enabling the draft-rigging to be made of standard size and adapting it for use on heavy or light rolling-stock by the simple substitution 35 of different wedge-blocks.

The action of the friction-surfaces in addition to the increased resistance secured is to make the movement of the draft-bar sluggish, thereby preventing backlash or oscillation 40 of the cars, and at the same time a full range of movement is permitted. The inclines of the wedge-blocks meet at the center line of transverse movement of the wedge-blocks C, and consequently there is little 45 tendency of said blocks to tilt and bind in their guides, and any such binding is further prevented by long friction-bearings on the sides of said wedge-blocks.

Having thus described my invention, what 50 I claim as new, and desire to secure by Letters Patent, is—

1. In a draft-rigging for railway-cars the combination with a draw-bar, wedge-blocks having working faces inclined in opposite directions to the line of draft and connected to move in both directions in unison with said draft-bar, of oppositely-located transversely-movable wedge-blocks having working faces corresponding to the working faces of the 55 wedge-blocks moving with the draft-bar, and adapted to coöperate therewith on opposite sides and independent springs for said transversely-movable wedge-blocks for moving them toward each other; substantially as described.

2. In a draft-rigging the combination with a draft-bar, wedge-blocks having working faces

inclined in opposite directions to the line of draft and mounted to move in unison with said draft-bar in both directions, transversely-movable wedge-blocks having correspondingly-inclined working faces, springs for advancing said transversely-movable wedge-blocks and a through-bolt passing centrally through all of said wedge-blocks for confining the springs; substantially as described. 70

3. In a draft-rigging the combination with a draft-bar, wedge-blocks having operative faces inclined oppositely to each other on each side of the line of draft, transversely-movable wedge-blocks having correspondingly-inclined operative faces, springs for advancing said transversely-movable wedge-blocks and a through-bolt arranged transversely of the line of draft for confining the springs and holding the transversely-movable wedge-blocks in operative position; substantially as described. 85

4. In a draft-rigging the combination with a housing having means for attachment to the car-frame and transversely-extending guides, of a draft-bar, wedge-blocks mounted to move in unison with said draft-bar and having oppositely-inclined working faces on each side of the line of draft, transversely-movable wedge-blocks mounted in said transverse guides and having correspondingly-inclined working faces, independently-removable caps for the outer ends of the transverse guides and springs interposed between said caps and transversely-movable wedge-blocks; substantially as described. 95

5. In a draft-rigging the combination with a housing having transversely-extending guides, transversely-movable wedge-blocks supported in said guides, caps on the outer sides of said transversely-movable wedge-blocks, springs interposed between said caps and wedge-blocks and a through-bolt passing through said caps and wedge-blocks for retaining the parts in their operative positions, of a draft-bar and wedge-faces moving in unison therewith for coöperating with the transversely-movable wedge-blocks; substantially as described. 105

6. In a draft-rigging the combination with the housing having transversely-extending guides and a central longitudinally-extending channel-way for the draft-bar with stops at opposite ends of said channel-way, of transversely-movable wedge-blocks mounted in said guides, springs for advancing said wedge-blocks toward each other, a draft-bar, wedge-blocks moving in both directions in unison with said draft-bar and having oppositely-inclined operative faces on each side of the line of draft for coöperating with the transversely-movable wedge-blocks and stop-surfaces adapted to coöperate with the stops on the housing for limiting the longitudinal movement of the draft-bar; substantially as described. 110

7. In a draft-rigging for railway-cars, the combination with a housing formed of a sin-

- gle casting having transversely-extending guides and a central channel-way with stop projections in said channel-way, of transversely-movable wedge-blocks mounted in 5 said guides and having friction-bearings therein and springs for advancing said wedge-blocks, of a draft-bar having wedge-blocks connected for moving in unison therewith in both directions and provided with working 10 faces inclined in opposite directions on both sides of the line of draft and stop-surfaces adapted to contact with the stop-surfaces in said channel-way for limiting the movement of the draft-bar; substantially as described.
- 15 8. In a draft-rigging for railway-cars the combination with the draft-bar, wedge-blocks moving in unison therewith in both directions and having working faces inclined in opposite directions on each side of the line of draft, of 20 transversely-movable wedge-blocks, springs for advancing said wedge-blocks and guides for said wedge-blocks having frictional bearing-surfaces for retarding the transverse movement of the wedge-blocks; substantially 25 as described.
9. In a draft-rigging, the combination with a longitudinally-movable draft-bar and transversely-movable blocks moved transversely by the longitudinal movement of said draft- 30 bar, of fixed guides for said transversely-movable blocks having friction-surfaces for retarding such movement and springs for advancing the blocks; substantially as described.
- 35 10. In a draft-rigging for railway-cars the combination with the draft-bar having wedge-blocks connected therewith for unitary movement in both directions and oppositely-inclined working faces on said wedge-blocks, 40 said inclined working faces meeting at a central point, of transversely-movable wedge-blocks having oppositely-inclined working faces extending from the side approximately to a central point whereby the tendency to 45 tilt said transversely-movable wedge-blocks by the longitudinal movement of the draft-bar is reduced, and springs for advancing the transversely-movable wedge-blocks to resist the longitudinal movement of the draft-bar; 50 substantially as described.
11. In a draft-rigging the combination with the housing having the transversely-extending guides with the substantially-plane guiding-surfaces on front and rear sides, of a longitudinally-movable draft-bar, wedge-blocks 55 movable in unison therewith and having oppositely-inclined working faces, transversely-movable wedge-blocks coöperating with the longitudinally-movable wedge-blocks and 60 having oppositely-located plane friction-surfaces at front and rear for coöperating with the plane surfaces in the guides and springs for advancing the transversely-movable wedge-blocks; substantially as described.
- 65 12. In a draft-rigging the combination with the longitudinally-movable draft-bar, the wedge-block mounted to move in unison there-

with and having centrally-arranged elongated opening, of a transversely-movable wedge-block, a spring for advancing said wedge-block and a through-bolt for compressing said spring passing through said elongated opening in the longitudinally-movable wedge-block; substantially as described.

13. In a draft-rigging for railway-cars the 75 combination with a draft-bar, a yoke carried by said draft-bar, independent wedge-blocks mounted in said yoke on opposite sides of its longitudinal center and having recesses therein with oppositely-inclined wedging-surfaces, 80 of transversely-movable spring-pressed wedge-blocks having projecting oppositely-inclined surfaces coöperating with the corresponding surfaces of the wedge-blocks mounted in the yoke; substantially as described. 85

14. In a draft-rigging the combination with the draft-bar, the yoke connected therewith, oppositely-arranged wedge-blocks mounted in said yoke and each having a projecting bearing-point for coöperation with the bearing-point on the other block for permitting of a limited rocking movement in the yoke of oppositely-arranged transversely-movable wedge-blocks and springs for advancing the same; substantially as described. 95

15. In a draft-rigging the combination with an integral housing having a central channel-way for the draft-bar, transversely-extending guides and a series of vertically-extending apertures for the supporting-bolts whereby 100 the housing may be applied to car-frames of different builds, transversely-movable wedge-blocks in said guides and springs for advancing said wedge-blocks, of a longitudinally-movable draft-bar mounted in said channel-way and wedge-blocks moving in unison with 105 said draft-bar for coöperating with the transversely-movable wedge-blocks; substantially as described.

16. In a draft-rigging for railway-cars the 110 combination with an integral housing having a central draft-bar channel-way and transversely-extending guides as described, of transversely-movable wedge-blocks mounted in said guides and having inclined wedging-faces at front and rear projecting into said channel-way with substantially horizontal top and bottom faces, of a longitudinally-movable draft-bar, wedge-blocks connected with said draft-bar and having webs overlying the substantially-horizontal surfaces of the transversely-movable wedge-blocks, 120 whereby the rear end of the draft-bar is held against vertical movement; substantially as described. 125

17. In a draft-rigging the combination with the housing having the transversely-extending guides and the draft-bar having the wedge-blocks connected therewith, of the transversely-movable wedge-blocks coöperating with the wedge-blocks moving with the draft-bar, springs for advancing said transversely-movable wedge-blocks, reversible caps for the ends of the guides beneath which 130

the springs are confined, said caps having projections on one side for reducing the size of the spring-box when turned inwardly; substantially as described.

5 18. A wedge-block for draft-rigging of railway-cars having a projection at one side for entering the draft-bar yoke, a shoulder N and a recess at the opposite side having plane oppositely-inclined wedge-surfaces; substantially as described.

10 19. A wedge-block for draft-rigging of railway-cars having a projection at one side for entering the yoke of a draft-bar, a shoulder N, a recess in the opposite side having plane inclined wedging-surfaces at front and rear and

a web at top and bottom of said recess; substantially as described.

20. A transversely-movable wedge-block for draft-rigging of railway-cars having a substantially-cylindrical outwardly-extending 20 portion constituting a spring-box and an inwardly-extending projection having oppositely-inclined plane wedging-surfaces with substantially-horizontal top and bottom surfaces; substantially as described.
